UNITED STATES PATENT OFFICE.

DAVID HINDAHL, OF CHICAGO, ILLINOIS, ASSIGNOR TO RODGER BALLAST CAR COMPANY, OF CHICAGO, ILLINOIS, A CORPORATION OF MAINE.

CONVERTIBLE DUMP CAR.

1,416,711.

Specification of Letters Patent. Patented May 23, 1922.

Application filed March 29, 1922. Serial No. 547,634.

To all whom it may concern:

Be it known that I, DAVID HINDAHL, a citizen of the United States, residing at Chicago, in the county of Cook and State of Illinois, have invented certain new and useful Improvements in Convertible Dump Cars, of which the following is a specification.

This invention relates to a new and improved convertible dump car and more particularly to an end construction for such cars.

As is well known in the art, various forms of convertible cars are in use, the end portions of which over the trucks are provided with relatively flat fixed floors while the portion between the trucks is provided with varying types of dump doors and hopper constructions. In certain positions of the center floor construction, a flat floor, substantially continuous with the flat floor ends, is provided. In other positions of the floor elements, varying types of hoppers are formed in the center portion of the car.

With cars of this general character, when the car is used with the substantially flat floor throughout, it is ordinarily desirable to have the greatest possible floor area and consequently the end of the car should be located at the extreme end of the car frame. On the other hand, when the central portion of the car is so utilized as to form hoppers, it is often desirable that an auxiliary end be formed within the car at the point of junction between the central hopper portion and the flat floor ends of the car. Such a location of the auxiliary ends is desirable in order that the entire contents of the car may be discharged through the hoppers and further where heavy material is handled, the weight carrying capacity of the car will often be fully utilized by a load intermediate the inwardly spaced ends.

Certain prior forms of cars have been designed having supplemental end portions which may be swung into place at the ends of the hopper portion and other forms of cars have been constructed in which the car ends are movable bodily from the extreme end of the car to the inner end of the flat floor over the trucks.

Where supplemental swinging or otherwise movable ends are provided, the car construction is complicated and considerable

additional weight is required. Where the car end is moved bodily, the car structure is considerably weakened since the connections between the ends and sides when detachable in character are not as efficient as a permanent structure and further since when the ends are moved inwardly the sides are not adequately cross-connected at the extreme ends of the car.

It is an object of the present invention to provide a car construction whereby a removable end may be placed at a desired intermediate portion of the car, such end comprising elements of the normal end construction, the normal end construction being so designed as to permit removal of these elements without structurally weakening the permanent end.

It is a further object to provide a construction of this character in which the movable elements are of such size as to be readily handled whereby the change in effective end location may be accomplished rapidly and with a small expenditure of labor.

Other and further objects will proceed as the description proceeds.

Broadly, my invention comprises an end construction in which the end framing elements are permanently secured in place and in which the end wall forming elements or a portion thereof are readily removable from association with the framing elements.

I have illustrated a preferred embodiment of my invention in the accompanying drawings, in which—

Figure 1 is a side elevation showing one end of a car constructed according to the present invention;

Figure 2 is an end view of the car shown in Figure 1; and

Figure 3 is a fragmentary section illustrating the construction.

The car shown in the drawings has flat floor portions 5 extending over the trucks at the ends of the car and has a hopper portion 6 extending intermediate the trucks. The side of the car consists of a truss frame 7 and wall forming elements 8, which latter are permanently secured to the frame. These portions of the car may be of any usual construction and the detail of the car shown forms no part of the present invention.

As shown in Figure 2, the end of the car

consists of an upper rail 9 which permanently connects the corner verticals 10 and which is further connected to the bottom cross member 11 by the vertical elements 12 and 13. The elements 13 are connected to the top rail by means of plates 14 which aid in stiffening the end frame construction. The lower wall member 15 is permanently secured to the frame.

10 The retaining member 16, as shown in Figure 3, is pivoted at 17 to the inside of the car side adjacent the rear face of the fixed end wall member 15. The element 16 is an angle bar having a flange 18 engaging the movable wall elements 19 and urging them against the various vertical members of the end frame. The flange 18 is provided at its upper end with the hook portion 20 which engages the upper surface of the upper removable wall member and prevents vertical displacement of said members. The dog 21 is pivoted at 22 to the inside of the car side and the cam surface 23 of the dog engages the inner edge of the retaining member 16 and maintains that member against the removable wall members 19.

As shown in Figure 1, a vertically extending U-member 24 is secured upon the inside of each car side at the points of junction between the hopper portion and the flat end portions of the car floor. The distance between the legs of the U is of a width adapted to receive the removable wall members 19. In the form shown, these removable wall members consist of wooden planks.

When it is desired to remove the wall members 19 from the end of the car, the dogs 21 are swung so as to permit the retaining members 16 to be swung about their pivots away from the end. The members 19 then may be readily lifted from place and are inserted in the guideways formed by the U-members 24. They are retained in place by gravity in these guideways.

45 Since each member 19 is comparatively small, its weight is not excessive and the movement of the end may be accomplished without great labor. It will be noted that when the members 19 are in place in the U-guides 24, the car side frame construction is effectively supported and connected by the permanent end frame elements which remain in place. There is thus no weakening of the car. The lower end element 15 which remains in place permanently serves to catch any material which may flow over the inner end in loading and to prevent such material from falling out of the car end. Due to the absence of any solid end above this fixed member, however, such material may be readily shoveled from the car.

The particular embodiment shown is to be understood to be illustrative only and it is my intention to cover all modifications com-

ing within the spirit and scope of the appended claims.

I claim:

1. In a railway car, a sectional end, certain of said sections being removable, and means located at points intermediate the car ends 70 adapted to retain said sections in place at such points.

2. In a railway car, permanent end frame members, end wall sections removably associated with said frame, and means located at 75 points intermediate the car ends adapted to retain said sections in place at such points.

3. In a railway car, permanent end frame members, an end wall removably associated with each such frame, and means located at 80 points intermediate the car ends adapted to removably retain said end walls in place at such points.

4. In a railway car, permanent end frames, end walls located inwardly of said frames, 85 means adapted to removably retain the walls in place adjacent the end frames, and supplemental means adapted to retain the walls in place at points intermediate the car ends.

5. In a railway car, permanent sides, permanent end frames connecting the sides, sectional end walls located inwardly of said frames, means adapted to removably retain the walls in place adjacent the end frames, and supplemental means adapted to retain 95 the walls in place at points intermediate the car ends.

6. In a railway car, permanent sides, permanent end frames connecting the sides, sectional end walls comprising vertically superposed horizontally extending members located inwardly of said frames, means adapted to removably retain the walls in place adjacent the end frames, and supplemental means adapted to retain the walls in place at 105 points intermediate the car ends.

7. In a railway car, permanent sides, permanent end frames connecting the sides, removable walls located against the inner side of the end frames, means adapted to maintain said walls in place against the frames, said means being adjustable to permit removal of the walls, and additional means adapted to support the walls at points intermediate the car ends.

8. In a railway car, permanent sides, permanent end frames connecting the sides, removable walls located against the inner side of the end frames, guides adapted to maintain the walls in place against the 120 frame, said guides being adjustable to permit removal of the walls, and U-shaped guides adapted to support the walls at points intermediate the car ends.

Signed at Chicago, Illinois, this 27th day 125 of March, 1922.

DAVID HINDAHL.
